ACTUATING MECHANISM FOR PRESSING MACHINES

Application filed August 9, 1929. Serial No. 384,694.

This invention relates to pressing machines such as garment and laundry presses and has for its object a particularly simple and efficient means for boosting the pressure applied to the movable pressing element, in addition to the pressure applied directly thereto by a prime mover.

The invention consists in the novel features and in the combinations and constructions hereinafter set forth and claimed.

In describing this invention, reference is had to the accompanying drawings in which like characters designate corresponding parts in all the views.

Figure 1 is a side elevation, partly broken away, of a pressing machine embodying my invention.

Figure 2 is an enlarged sectional view taken approximately on the plane of line 2—2, Figure 1.

Figure 3 is an elevation of the parts seen in Figure 2.

This invention comprises, generally, a stationary part arranged in the path of a part of the motion transmitting mechanism of the machine to actuate said part in addition to the motion imparted thereto by a prime mover in order to boost the pressure applied to the movable pressing element, one of said parts having a cam which effects the boosting operation when the parts engage and the motion transmitting part is being actuated by the prime mover.

I have here shown my invention as embodied in a conventional type of laundry press in which the cooperating pressing elements are a buck 1 and a head 2 movable toward and from the buck.

The buck 1 is mounted on a suitable bracket 3 which in turn is mounted upon a suitable frame 4. The head 2 is carried by a lever 5 pivoted at 6 between its ends to a standard 7 rising from the frame.

The buck is overlaid with a compressible padding 8, and the subject matter of this invention acts not only to boost the pressure to apply the heavy pressure but also it applies uniform heavy pressure regardless of the thickness of the work and the padding and the amount of compression of the padding.

The press is here shown as actuated by power, that is, the prime mover is a motor and the motion transmitting means between the motor and the movable pressing element or head 2, in addition to the lever 5 comprises toggle links 9, 10, the link 9 being connected by a pivot at its upper end at 11 to the rear arm of the lever 5 and the link 10, by a pivot at 12 at its lower end to the base of the frame. The links 9, 10 are pivoted together by a joint permitting relatively endwise movement of the link 9 to give a boosting action to the straightened toggle.

The links are here shown as connected together by a pin-and-slot connection, the link 9 being provided with the pin 13 at its lower end which works in lengthwise slots 14 provided in the upper bifurcated end of the link 10. The lower end of the link is also formed bifurcated and a roller 15 is mounted on the pin 13 between the bifurcations thereof, the roller being mounted eccentrically on the pin 13.

16 is a stationary track mounted on a bracket 17, the track being curved about a center substantially on the axis 12 but preferably formed to give a slight cam action as will be later described. This track is arranged in the path of the roller 15, the bracket 17 extending between the bifurcations of the lever 10 and being provided with a suitable friction face 18.

After the toggle straightens the roller 15 coacts with the track and then during further straightening of the toggle, the roller rolls up the track, and being eccentrically mounted, moves the link 9 endwise relatively to the link 10 and thus boosts the pressure applied to the head carrying lever 5. The track 16 is also a cam and acts to boost the link 9 after the toggle has passed its dead center line.

The prime mover may be of any suitable form, size or construction. It is here shown as the rod 19 of a piston movable in an oscillating cylinder 20 pivoted at 21 to the frame. The piston rod 19 is pivoted at 22 to a forwardly extending arm 23 forming an angle lever with the toggle link 10. The flow of motive fluid, as compressed air, to and from

the cylinder is controlled in any suitable manner or by any suitable valve mechanism located in a casing 24.

25 is a push button for operating the valves to permit the flow of air to the cylinders and 26 is a trip lever for exhausting the air from the cylinder. The piston in the cylinder is single acting and the press is opened when the pressure in the cylinder is released by countersprings 27.

10 In operation, assuming that the press is open, the operator depresses the button 25, permitting air to enter into the cylinder 20 and through the piston and piston rod 19 and arm 23 moving the toggle from folded position toward straightened position where the roller 15 engages the track 16 or the friction plate 18 thereon.

During further straightening of the toggle, the roller 15 moves about its eccentric axis and thus boosts the link 9. The roller 15 rides along the track until full pressure is delivered or until the resistance of the work to the closing of the head 2 overcomes the pressure in the cylinder 20.

28 What I claim is:

1. In a pressing machine, a supporting frame, cooperating pressing elements, one of which is movable toward and from the other, means for actuating the movable element including a pair of toggle links and means for actuating the toggle, the links being pivoted together by a joint which is slidable to permit endwise movement of the link 35 connected to the movable element relatively to the other link, means including an engaging member on the endwise movable link and a stationary part carried by the frame and arranged to engage said member on the endwise movable link and move the link endwise after the toggle straightens.

2. In a pressing machine, a supporting frame, cooperating pressing elements, one of which is movable toward and from the other, 45 means for actuating the movable element including a pair of toggle links and means for actuating the toggle, the links being pivoted together by a joint permitting endwise movement of the link connected to the movable element relatively to the other link, a roller 50 mounted eccentrically on the endwise movable link and a stationary track carried by the frame in the path of the roller to engage and roll the same during the straightening 55 of the toggle.

3. In a pressing machine, a supporting frame, cooperating pressing elements, one of which is movable toward and from the other, means for actuating the movable element including a pair of toggle links and means for actuating the toggle, the links being pivoted together by a joint permitting endwise movement of the link connected to the movable element relatively to the other link, a roller 60 mounted eccentrically on the endwise mov-

able link and a stationary track carried by the frame in the path of the roller to engage and roll the same during the straightening of the toggle, said roller being located at the joint of the toggle.

4. In a pressing machine, a supporting frame, cooperating pressing elements, one of which is movable toward and from the other, a lever carrying the movable element, said lever being pivoted to the frame, toggle links 70 pivoted respectively to the frame and to said lever and being pivoted together by a joint permitting relatively endwise movement of the link pivoted to said lever, the endwise movable link having a rolling cam and a stationary track fixed to the frame and arranged in the path of said cam to engage and roll after the toggle straightens and means for straightening the toggle.

5. In a pressing machine, cooperating 85 pressing elements, one of which is movable toward and from the other, means for actuating the movable element including a prime mover and motion transmitting means between the prime mover and the movable element, a part of said motion transmitting means having a movement in addition to that imparted thereto by the prime mover, means for giving said part said additional movement including a stationary part carried by 90 the frame and arranged in the path of movement of said relatively movable part to engage and move the same in addition to the movement imparted thereto by the prime mover, one of said parts having a cam for 95 coacting with the other part.

6. In a pressing machine, cooperating 100 pressing elements, one of which is movable toward and from the other means for actuating the movable element including a prime 105 mover and motion transmitting means between the prime mover and the movable element, a part of said motion transmitting means having a movement in addition to that imparted thereto by the prime mover, means for giving said part said additional movement including a stationary part carried by 110 the frame and arranged in the path of movement of said relatively movable part to engage and move the same in addition to the movement imparted thereto by the prime 115 mover, the stationary part being a track, the other part having an eccentric roller movable on the track.

7. In a pressing machine, cooperating 120 pressing elements, one of which is movable toward and from the other, means for actuating the movable element including a prime mover and motion transmitting means between the prime mover and the movable element, a part of said motion transmitting means having a movement in addition to that imparted thereto by the prime mover, means for giving said part said additional movement including a stationary part carried by 125 130

the frame and arranged in the path of movement of said relatively movable part to engage and move the same in addition to the movement imparted thereto by the prime mover, one of said parts having a rolling cam for coacting with the other part and arranged to be rolled by the movement of the motion transmitting part by the prime mover.

5 In testimony whereof, I have hereunto signed my name at Syracuse, in the county of Onondaga, and State of New York, this 10 9th day of July, 1929.
